US0D1093282S

(12) **United States Design Patent** (10) **Patent No.:** **US D1,093,282 S**
(45) **Date of Patent:** **** Sep. 16, 2025**

(54) **JUMP STARTER BATTERY PACK**

(71) Applicant: **THINKCAR TECH CO., LTD.**,
Shenzen (CN)

(72) Inventors: **Tao Lin**, Shenzen (CN); **Cheng Zhang**,
Shenzen (CN)

(73) Assignee: **THINKCAR TECH CO., LTD.**,
Shenzen (CN)

(**) Term: **15 Years**

(21) Appl. No.: **29/914,103**

(22) Filed: **Oct. 13, 2023**

(51) LOC (15) Cl. **13-02**

CLAIM

The ornamental design for a jump starter battery pack as shown and described.

DESCRIPTION

FIG. 1 is a front perspective view of a jump starter battery pack showing the new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a detailed view of FIG. 1.

The broken lines in the drawings are included for the purpose of illustrating portions of the jump starter battery pack that form no part of the claimed design.

1 Claim, 9 Drawing Sheets
